UNITED STATES PATENT OFFICE.

WILLIAM F. DUNCKER, OF WRIGHTSVILLE, PENNSYLVANIA, ASSIGNOR OF
ONE-THIRD TO JACOB OHMIT AND ONE-THIRD TO STEVEN WILSON, OF
WRIGHTSVILLE, PENNSYLVANIA.

INTESTINE-CLEANER.

No. 846,406.

Specification of Letters Patent.

Patented March 5, 1907.

Application filed November 6, 1905. Serial No. 286,021.

To all whom it may concern:

Be it known that I, WILLIAM F. DUNCKER, a citizen of the United States, and a resident of Wrightsville, in the county of York and State of Pennsylvania, have made certain new and useful Improvements in Intestine-Cleaners, of which the following is a specification.

My invention consists in an improvement in machines for cleaning intestines of hogs, beef, and sheep for casing of sausage, &c.; and the invention consists in certain novel constructions and combinations of parts, as will be hereinafter described and claimed.

In the drawings, Figure 1 is a vertical longitudinal section, and Fig. 2 a top plan view, of a machine embodying my invention. Fig. 3 is a side elevation thereof. Fig. 4 is a cross-section on about line 4 4 of Fig. 1. Fig. 5 is a detail sectional plan view of the device for turning the casings. Fig. 6 is a detail vertical section on about line 6 6 of Fig. 5. Fig. 7 is a detail perspective view of one of the scrapers. Fig. 8 is a detail perspective view of the revolving feeder for the casing-turner, and Fig. 9 is a cross-section on about line 9 9 of Fig. 1; and Fig. 10 is a detail perspective view of the presser.

In constructing the machine I employ a suitable framing, which may comprise side plates A A', as shown in Figs. 1, 2, 3, 4, and 9. In suitable bearings in the framing I journal the feed-rollers B B' near one end of the machine, and the bearings of the roller B' may be adjustable by means of a screw B², (see Figs. 1 and 4,) so the rollers may be caused to press upon the casings with more or less tension, as occasion may require.

The upper roller B is supported at one end in the side plate A and at its other end in a bracket B³, so the casings may be inserted at B⁴ between the rollers B and B' and may be removed at the same point whenever desired, as will be understood from Figs. 2 and 4 of the drawings. A feed-board B⁵ leads up to the rollers B and B' and supports the casings as they pass to said roller, pins B⁶, projecting upwardly from the board B⁵, forming guides for the casings as they pass to the rollers. The rollers B B' may be termed the "front" feed-rollers, and in rear thereof I provide a second pair of feed-rollers C C', constructed and supported similarly to

the rollers B B', the lower roller being arranged for adjustment by screws C² and the upper roller being supported in a bracket C³, so one end of the roller C will be unobstructed, and an inclined feed-board C⁵, having guide-pins C⁶ leading up to the rollers C and C', as best shown in Fig. 1 of the drawings. 60

Between the front and rear feed-rollers I provide a pair of scrapers, one below the other and preferably nearer the front feed-rollers, as shown in Fig. 1. The lower scraper D and the upper scraper E are constructed alike, but are arranged with their blades reversed, so that the lower scraper may properly operate upon the under side of the casings while the upper scraper operates upon the upper side of the casings, so that I secure a pressure upon both sides of the casings. The scrapers D and E are journaled in the framing and are turned positively by the gearing, presently described, in the directions indicated by the arrows in Fig. 1, with their blades D' E' inclining rearwardly with respect to the direction of revolution of the scraper. These scrapers are alike and the description of the scraper D (shown in Fig. 7) will answer for both scrapers. The scraper D includes a central body or core, made polygonal and preferably octagonal, as shown, and the blades D' are secured at their inner ends to the flat faces D² of the body portion or core, so that the blades project in approximately a tangential direction and incline, as will be understood from the arrows in Fig. 1, rearwardly with respect to the direction of revolution of the scraper, so that the blades will operate with a scraping action against the casings, and these blades being made in the form of open frames and of spring material are resilient, so that I avoid any injury to the casings or tearing thereof by the revolution of the scrapers in the operation of the machine. 85

By making the blades in the form of open frames I not only increase their resilience, but I also provide for the free discharge of water upon the casings and through the blades in the use of the machine, as more fully described hereinafter.

In connection with the scrapers I provide means for pressing the intestines toward the blades of the pair of scrapers. This pressing means preferably comprises a handle-lever F, pivoted at F', arranged at F² to engage

with a rack F^3 on the side plate A and provided below its pivot F' with the oppositely-projecting plates d and e , which are spaced apart at their adjacent ends, where they are 5 secured to the lever F by means of the brackets d' and e' , so that a way is provided between the adjacent ends of the pressing-plates for the passage of the casings in the use of the invention. As these plates d and e 10 project in opposite directions with respect to the pivot F' of the presser, it will be noticed that by tilting the presser on its pivot F' the plates d and e will be adjusted toward and from their respective scrapers and with uniform pressure, and the detent at F^2 , which 15 may be of any suitable form of pawl engaging with the rack F^3 , will hold the device in any desired adjustment. By this means the casing passes through the machine, and being 20 fed by the rollers B B' C C' it will be scraped on its lower and upper sides by the scrapers D and E operating against the pressing-plates d and e , and in this connection it will be noticed that the scrapers are provided 25 with resilient blades, and the pressers are practically unyielding, and the regulation of pressure is secured by the adjustment of the pressing devices, as before described.

In the making of large casings it is desirable 30 to turn them inside out, and to this end I provide the turning device G in rear of the feed-rollers C and C' and also provide above the turning device G a feed-roller H and between said feed-roller and the roller C a 35 guide-rod I and a swinging gate J above the same and adapted to hold the casings when they are being applied to the turning device. The feed-roller H is provided with a series of plates H' , notched in their outer edges at H^2 40 and forming clasps to engage the casings and feed them down to the turning device G.

The turning device G comprises a series of arms G' , secured at their lower ends at G^2 , springing outwardly at their upper ends at 45 G^3 , together with a compressor by which the ends G^3 may be forced toward each other to receive one end of the casing and then be released to spring out within said end and hold it while the casing is being turned inside out 50 in the operation of the machine. The compressor includes a ring K, sliding along outwardly-inclined portions G^4 of the arms G' , so that when the compressor is in its lower position, as shown in Fig. 6, the arms G' 55 should be free to spring outwardly at their upper ends, but may be contracted by the upward movement of the ring K by its lever K' , so the upper ends of the arms will be contracted to permit the end of the casing to be 60 slipped readily thereover. In the illustration shown in Fig. 6 the casing is illustrated in the act of being turned inside out, the weight of the casing aiding such action and a stream of water discharged from the nozzle 65 L' facilitating the operation as it is dis-

charged into the pocket formed by the turning of the casing, and thus serves as a feeder as well as a cleansing agent, as will be understood from Fig. 6 of the drawings.

In driving the several parts the upper and lower rollers B B' and C C' are geared together, as will be understood from Fig. 4. The feed-roller H is provided with a sprocket-wheel 1, the lower roller C' is provided with a sprocket-wheel 2, the scraper E is provided with a sprocket-wheel 3, the scraper D is provided with a sprocket-wheel 4, and the lower roller B' is provided with a sprocket-wheel 5, and the chain 6 is disposed over these sprocket-wheels in such manner, as illustrated in Fig. 75 3, as to drive the said parts in the directions indicated by the arrows in Figs. 1 and 3, motion being given in any suitable manner to any one of the drive-pulleys 1 to 4, as will be understood by those skilled in the art. Ordinarily this may be effected by means of a band operating upon the pulley 6, as shown in Figs. 3 and 4.

In supplying water to wash the casings at the different stages I employ a main M in the 90 form of a pipe extending alongside the plate A. This main M has upper and lower branches M' and M'' , being returned at M^3 and provided with the inwardly-projecting discharge-pipes M^4 and M^5 , discharging through their 95 perforations toward the rollers B and B', the discharge-pipes M^6 and M^7 discharging, respectively, to the scrapers D and E, the pipes M^8 and M^9 discharging, respectively, to the rollers C and C', and the pipe L^2 , having the downwardly-directed nozzle L' , discharging to the casing as it is being turned inside out. By this construction I am able to keep the feed-rollers and scrapers clean and also supply water to wash the casings as they are passing through the machine.

Having thus described my invention, what I claim as new, and desire to secure by Letters Patent, is—

1. The combination substantially as herein described of front and rear feed-rollers, a pair of upper and lower scrapers arranged between the front and rear feed-rollers and spaced apart, and pressing devices operating between the scrapers and comprising plates 110 projecting across their respective scrapers and spaced apart at their adjacent ends to form a way for the casings, a pivoted support for said plates, and means whereby the support may be rocked and set the plates toward and from their respective scrapers, substantially as and for the purpose set forth.

2. The combination in a machine, substantially as described of a pair of scrapers spaced apart, and a pressing device between said scrapers and having pressing-sections connected together and corresponding to the spaced-apart scrapers and movable jointly toward and from their respective scrapers the respective pressing devices being spaced 125 130.

apart to form a passage for the casings, substantially as set forth.

3. The combination of a pair of scrapers and a presser pivoted between the said scrapers and having opposite pressing-sections corresponding to their respective scrapers and a support to which said pressing-sections are secured, and means whereby the support may be shifted to set the pressing-sections toward and from their respective scrapers the respective pressing devices being spaced apart to form a passage for the casings, substantially as set forth.

4. The combination of a presser having opposite pressing-sections and pivoted between the same, a scraping-section on one side of one pressing-section, and a scraping-section on the opposite side of the other pressing-section the respective pressing devices being spaced apart to form a passage for the casings, substantially as set forth.

5. The combination, of a pair of scrapers spaced apart, a pressing device pivoted between said scrapers and comprising pressing-plates projecting adjacent to their respective scrapers and spaced apart at their adjacent ends to form a passage between them for the casings, substantially as set forth.

6. The combination of the front feed-rollers, the rear feed-rollers, the upper and lower scrapers between said front and rear rollers, the presser between the upper and lower scraper and having pressing-sections opposite their respective scrapers, said pressing-sections being spaced apart at their adjacent ends for the passage of the intestines between them and means whereby the pressing-sections may be adjusted toward and from their respective scrapers.

40 7. The combination in a machine substantially as described of the feed-rollers, the scraping-rollers, the pressing devices extending across their respective scraping-rollers and adapted to press the intestines against the same and a water-supply pipe having discharge devices extending adjacent to their respective feed-rollers and scraping-rollers the respective pressing devices being spaced apart to form a passage for the casings, substantially as set forth.

55 8. In a machine for cleaning intestines, a turning device for turning the intestines inside out and comprising a series of arms secured at one end and movable toward and from each other at their free ends the latter being arranged at the receiving end of the turning device, the arms being adapted to spring apart at said free ends to bind within and expand the end of an intestine, and 60 means for compressing the arms to contract such ends to permit their insertion within such end of the intestine, substantially as set forth.

65 9. The combination in a machine, substantially as described, with the turning device

comprising the expandible arms and means for compressing the same, of a water-delivery nozzle above the said arms and adapted to deliver water to the casing in the turning device, whereby to facilitate the turning of said 70 casing, substantially as set forth.

10. The combination in a machine, substantially as described, of a device for turning the intestines, a feeding-roller above said turning device and adapted to deliver the intestine thereto and a guide-rod and gate in advance of said feed-roller for holding the casing while it is being applied to the turning device, substantially as set forth.

15 11. The combination in a machine substantially as described with a pair of scrapers having yielding blades spaced apart, of a presser between said scrapers and comprising a pivoted support and unyielding plates projecting in opposite directions therefrom and 85 adjacent to their respective scrapers the respective pressing devices being spaced apart to form a passage for the casings, substantially as and for the purpose set forth.

20 12. The combination in a machine, substantially as described, of the front and rear feed-rollers, the upper and lower scrapers between said front and rear rollers, the rocking presser having pressing-sections extending adjacent to their respective scrapers, a guide 90 I and gate J in rear of the rear feed-rollers, the carrying-roller H in rear of the guide I, the device for turning the casings and located below the carrier H and a nozzle for delivering water to the casing held by the turning 100 device the respective pressing devices being spaced apart to form a passage for the casings, all substantially as and for the purpose set forth.

25 13. The combination in a machine substantially as described with a turning device having means for holding one end of the intestine, such intestine-holding means being spaced apart whereby the intestine or casing may be suspended from and dropped between them to form a pocket, of a water-delivery nozzle above the said device and adapted to deliver water into a pocket formed by the turning of the casing, whereby to form a feeder for the casing, substantially as set 115 forth.

30 14. The combination with a pair of scrapers spaced apart, of a pressing device arranged between said scrapers and having pressing-plates to coöperate with their respective scrapers and having an opening between the said pressing-plates for the passage of the intestines through the pressing device in the passing thereof between the two scrapers.

WILLIAM F. DUNCKER.
